**PILE SHELL BOOT AND MANDREL PLUG
POINT ASSEMBLY**
John J. Dougherty, Cedar Grove, N.J.
(262 Rutherford Blvd., Clifton, N.J.)
Filed Apr. 21, 1961, Ser. No. 104,579
1 Claim. (Cl. 61—53)

This invention relates generally to the art of piling and more particularly to a pile shell boot and mandrel point assembly that is adapted to drive a pile shell and at the same time initially to center the mandrel in the shell and to maintain the mandrel centered through the driving operation.

In driving a pile section down into the soil with ordinary mandrels, there is a tendency for the bottom of the mandrel to vibrate against the side of the shell section and damage and tear the side of the shell section permitting sand and water to enter the shell section whereby the mandrel becomes jammed in the shell with consequent loss of time and money to extract the mandrel.

Many expedients have been resorted to in order to solve this problem. Despite all such expedients, however, the cost of extracting such mandrels runs into thousands of dollars per year so that the problem has not by any means been solved. The fact remains that a mandrel operating at high speeds will necessarily so vibrate the shell section as to cause wear and tear thereupon, and my present invention has as its primary object the provision of a pile shell boot and mandrel point assembly by virtue of which the vibratory forces and impact shocks created by the operation of the mandrel in the shell section will be so controlled or will be directed into the center of the shell section so as to counteract so far as possible the bad effects of these forces upon the shell section.

Another object of the present invention is to provide a pile shell boot and a mandrel point assembly that avoids the disadvantages of prior driving operations by centering the mandrel during its travel whereby uniform driving pressure is brought to bear against the shell and boot and whereby greater penetration is provided.

Another object of the invention is to provide a mandrel plug point that is adapted to fit various shapes of pile shell boots.

Yet another object is to provide a pile shell boot with means for reinforcing the boot.

For further comprehension of the objects and advantages of the invention, reference will be had to the accompanying drawings and the following description taken in connection with the appended claims.

In the accompanying drawings forming a material part of this disclosure;

FIG. 1 is a vertical sectional view through the bottom of a pile shell section and the bottom of a mandrel embodying one form of the present invention.

FIG. 2 is a bottom plan view of the pile shell boot of the assembly.

FIG. 3 is a sectional view taken on the line 3—3 of FIG. 2.

FIG. 4 is a side elevational view thereof.

FIG. 5 is a sectional view taken on the line 5—5 of FIG. 6.

FIG. 6 is a top plan view of an assembly having a modified form of shell boot and a modified form of mandrel driving end.

FIG. 7 is a view similar to FIG. 5 showing a modified form of pile shell boot and a modified form of mandrel plug point.

FIG. 8 is a bottom plan view thereof.

FIG. 9 is a view similar to FIG. 5 showing an assembly with a modified form of shell boot and a modified form of mandrel driving end.

2

FIG. 10 is a plan view as seen from the line 10—10 of FIG. 9.

FIG. 11 is a view similar to FIG. 8 of an assembly having a modified form of shell boot and a modified form of mandrel point.

FIG. 12 is a view similar to FIG. 4 showing a modified form of shell boot.

Referring in detail to the drawings, in FIG. 1 the bottom end of a pile shell section 31 and the bottom end of a driving mandrel 36 embodying the invention are shown, the mandrel being shown in operative position inside the shell section. The shell section and mandrel embody a new and useful shell boot and mandrel point assembly.

15 The novel pile shell boot of the assembly is designated generally by the reference numeral 15. In FIG. 1, the shell boot 15 is shown fastened to the bottom of a pile shell section 31 of the helical type by welding 33.

A conventional driving mandrel 37 of the expandable 20 type with segments 36 and with a helical rib 38 on the outside thereof is shown in driving position on the shell boot 15. The novel mandrel point of the assembly comprises a base-plate 39 on the bottom end of the mandrel and secured thereto by a central tube 35 depending from 25 a block 38. The plate 39 is formed with a solid point 41 welded or secured thereto in any suitable manner. The point 41 is tapered with its base portion secured to the underside of the plate and is of a diameter such as to leave a space between it and the outer periphery of the 30 plate. The segments of the mandrel rest on the plate 39 leaving a space 52 between the segments and the body of the shell section 31.

As shown in FIGS. 2 to 4, inclusive, the novel pile shell boot 15 comprises a frusto-conical hollow body 17 open at the top and coming to a blunt point 19 closure at the bottom. A flat circular flange or plate 21 is formed radially around the periphery of the body. An annular formation 23 is formed on the top surface of the flange 21 around the inner periphery thereof, the outer periphery of the formation 23 being spaced inwardly from the outer periphery of the flange leaving a space 25. Radial ribs 27 are formed on the outer surface of the body 17 extending from the point 19 thereof to the outer periphery of the flange 21. Four such ribs are shown. 45 These ribs stiffen and reinforce the shell boot body.

As shown in FIG. 1, the flat bottom of the block or plate 39 of the mandrel rests upon the flat upper surface of the formation 23 on the flange 21 of the shell boot 15, with the tapered point 41 on the plate fitted snugly in 50 the hollow body 17 of the shell boot 15.

During the driving operation, the mandrel 37 rests evenly on the shell boot 15, and its tapered point 41 will strike the bottom of the body 17 of the boot at its center and if it should strike the body 17 at the side, 55 the tapered point 41 will be forced toward the center. In other words, the mandrel and its point 41 will be automatically centered during the driving operation. The clearance provided by the space 52 permits the mandrel to expand within reasonable limits without damage to the shell section.

In FIGS. 5 and 6, a modified form of pile shell boot 15' is shown. In this form, the body 17' is inverted 60 conical in shape, opening at the bottom and blunt point at the closed top 19' as viewed in FIG. 5. An annular formation 23' on the annular flange 21' of the body at the juncture of the body and the flange is dimensioned so as to leave a space 25' at the periphery of the flange. Spaced reinforcing ribs 27' extend along the bottom surface of the flange 21' and on the inner surface of the body 17'. The body 17' extends into a similarly shaped recess 54 in the circular block or plate 39' suitably fastened to the bottom of the mandrel 37'. The bottom flat

surface of the block or plate rests upon the flat top surface of the formation 23' for driving the boot 15' into the soil.

The modified form of shell boot 15^a shown in FIGS. 7 and 8 differs from the form of FIG. 1 merely in that the body 17^a is solid with a central square-shaped recess 45 to receive a similarly shaped protuberance 41^a on the plate 39^a constituting a modified point of the mandrel 37^a.

In FIGS. 9 and 10, another modified form of assembly is shown comprising a modified form of shell boot 15^b having a flat circular plate-like body 17^b with a circular formation 23^b on the top surface thereof, leaving a peripheral space 25^b. Spaced horizontal reinforcing ribs 27^b are formed on the under surface of the body. A central upstanding post 47 square in cross-section is formed integrally with the plate-like body and is adapted to be received in a similarly shaped recess 45^b in the base plate 39^b of the mandrel.

The modified form of assembly shown in FIG. 11 is the same as the form of FIGS. 7 and 8, except that the boot 15^x is hexagonal in configuration, and the mandrel point 41^x on the base plate 39^x is hexagonal.

The modified form of shell boot 15^{xx} shown in FIG. 12 is similar to the form of shell boot 15 of FIG. 1 except that no ribs 27 are shown. This boot 15^{xx} is to be used with a mandrel point such as the point 41 of FIG. 1.

In an emergency, a sleeve 50 may be slipped over the shell section 31 and seated on flange 21 as shown in FIG. 1 when the soil is tough and the driving is hard.

While I have illustrated and described the preferred embodiments of my invention it will be understood that changes in details of construction might be made without departing from the principle of the invention and I desire to be limited only by the state of the prior art and the appended claims.

I claim:

In combination, a pile boot and driving end of a mandrel body, said boot having a solid, flat, circular plate-

like body, a circular enlargement on the top surface of the body of said boot and having its periphery spaced inwardly of the boot body, a post, square in cross-section, upstanding from said body and enlargement and disposed centrally thereof, spaced radial ribs extending downwardly from the bottom surface of the plate-like body having their lower edges disposed in a plane parallel to the under surface of the plate-like body, and a base plate on the driving end of a mandrel body, said base plate having a recess of a shape and dimension fitting snugly about the upstanding post with the lowermost surface of said base plate resting upon the enlargement of the boot.
